GRINDING MACHINE HAVING A MOTOR DRIVEN WHEEL SPINDLE

Filed May 18, 1932

UNITED STATES PATENT OFFICE

1,948,848

GRINDING MACHINE HAVING A MOTOR
DRIVEN WHEEL SPINDLEHoward W. Dunbar, Worcester, Mass., assignor
to Norton Company, Worcester, Mass., a corpora-
tion of Massachusetts

Application May 18, 1932. Serial No. 612,003

2 Claims. (Cl. 51—166)

This invention relates to grinding machines, and more particularly to a grinding wheel slide spindle bearing and driving mechanism having an integral built-in driving motor with an air circulating system for cooling the same.

Heretofore, grinding machine spindles have been driven in different ways, such as an overhead belt drive, a belt drive from a drive shaft within the base of the machine, and a belt drive from a motor driving a main shaft on the wheel slide or the rear of the machine. These constructions have all involved a flexible driving connection between the prime mover and the driven spindle. A flexible driving medium, such as a belt or chain, necessitates attention on the part of the operator in maintaining it in proper driving condition so that the tension of the belt will insure a constant and uniform rotation of the wheel spindle. As the belt wears and ages, its driving qualities become less efficient.

It is the primary object of this invention to minimize these difficulties and to provide a built-in motor drive for a grinding wheel spindle, in which a flexible driving medium is eliminated.

It is a further object of this invention to provide a built-in motor drive for a grinding wheel spindle, in which the stator of the motor is removably supported in an enlarged portion of the wheel slide and in which the rotor surrounds and is fixedly mounted to rotate with the wheel spindle.

It is a further object of this invention to provide a self-contained coolant system for circulating air around and between the motor parts to cool the same during grinding.

Other objects will be apparent from the following disclosure. One embodiment of this invention has been illustrated in the accompanying drawing, in which like reference numerals indicate like parts.

Fig. 1 is a fragmentary cross-sectional view, through a grinding machine wheel slide embodying this invention;

Fig. 2 is a fragmentary front elevation on the machine, having parts broken away and shown in section to more clearly show the support for the wheel slide and its actuating mechanism;

Fig. 3 is a fragmentary cross-sectional view, taken approximately on the line 3—3 of Fig. 2; and

Fig. 4 is a fragmentary cross-sectional view, showing the support for the motor stator.

In accordance with this invention, a grinding machine is provided with a transversely movable wheel slide which rotatably supports a grinding

wheel spindle in adjustable bearings secured therein. An enlarged integral portion of the wheel slide is formed with a cylindrical bore which is arranged to support an electric motor stator. The grinding wheel spindle is arranged to support a motor armature in proper relation with the stator. An air circulating system is provided to circulate cool air around and between the motor parts to cool the same during the grinding operation. This mechanism comprises a fan mounted on the wheel spindle which is arranged to draw air from outside the enlarged portion and to force air through and around and between the motor parts and force the warm air out through apertures at the other end of the enlarged casing.

As illustrated in the drawing, a surface grinding machine, of the type disclosed in the prior patent to Norton No. 1,164,745 dated December 21, 1915, has been shown having a base 10 which is arranged to support a work table 11 for longitudinal movement thereon. A transversely movable wheel slide 12 is arranged to support a wheel spindle 13 in a pair of adjustable sleeve bearings 14 and 15 of standard construction, which are located at opposite ends of the slide 12. A grinding wheel 16 is mounted on the outer end of the wheel spindle 13. As illustrated in the drawing, the transversely movable wheel slide 12 is mounted in a vertically movable slide 20 which is arranged for adjustment vertically on a slideway 21 by means of a feed screw 22.

The wheel slide 12 is arranged for a transverse feeding movement which, as illustrated, comprises a rack bar 25 fixedly mounted on the slide 12 and a pinion 26 which is rotatably supported in the vertical slide 20 and meshes with the rack 25. The pinion 26 is mounted on one end of a rotatable shaft 27 which is journaled in the vertical slide 20. The other end of the shaft 27 is provided with a worm gear 28 which in turn meshes with the worm 29 on the shaft 30.

It is frequently necessary and desirable that the wheel be fed rapidly during some operations and slowly for truing the wheel or for a finishing operation. To accomplish this result, a hand wheel 31 is mounted on the outer end of the shaft 30 and is arranged so that it may be turned to rotate the shaft 30 directly to advance the wheel rapidly.

For a slow feeding movement, a hand wheel 35 is provided which is mounted on the outer end of a shaft 36. The inner end of the shaft 36 is provided with a worm 37 meshing with a worm gear 38 which is freely rotatable on a

reduced end portion of the shaft 30. By manipulation of a thumb nut 40, the operator may lock the worm gear 38 to the shaft 30 by forcing the friction plates 41 and 42 into frictional engagement with the side faces of the gear. After this has been done, the operator may then turn the wheel 35 and through the worm and worm gear reduction units produce a slow feeding movement of the grinding wheel slide.

10 The wheel slide 12 is provided with an enlarged integral casing 50 having a cylindrical bore 51 arranged to receive an electric motor stator 52 which is held in place by set screws 53. A motor rotor 55 is keyed to the tapered portion 56 of the spindle 13 and is held in place thereon by means of a locking collar 57. To permit ready access to the motor parts, the opening end of the cylindrical bore 51 is enclosed by an end cap 58 secured by screws to the end of casing 50 and which in turn supports the adjustable radial thrust bearing 15 and also an end thrust bearing 59. The adjustable bearing 14 is supported in an integral part of the wheel slide 12. The electric motor stator and rotor may be of any standard well-known constructions of constant speed, multi-speed or variable speed types.

In an encased built-in motor construction of this type, it is desirable that the parts of the motor be adequately cooled to maintain efficient operation of the machine. In the preferred construction, an air circulating system is provided, which includes a fan 60 which is fixedly mounted on a projecting portion 61 of the spindle 13 which is outside the radial bearing 15 and the end thrust bearing 59. The fan 60 is surrounded by a perforated guard 62 which in turn is fastened to the end cap 58. It will be readily appreciated from this construction that by removing the end cap 58 together with the bearing, the parts of the motor are made readily accessible. Air is drawn in through the perforation 63 in guard 62, passes through perforations 64 in the end cap and is directed by the funnel-shaped flange 65 to passages 66 in the armature, passages 67 outside the stator and also in the gap between the stator and the rotor. Air then passes out through the perforations 68 adjacent the other end of the enlarged integral motor casing.

75

The invention has been illustrated and described as applied to a surface grinding machine, but the invention is equally applicable to a cylindrical grinding machine, such as that shown in the expired patent to Norton No. 762- 80 838 dated June 14, 1904.

Having thus described the invention, what is claimed as new and desired to secure by Letters Patent is:

1. A grinding machine comprising a base, a wheel slide, a grinding wheel spindle rotatably supported on said slide, an adjustable bearing at one end of the slide to support the end of the spindle adjacent to the grinding wheel, an enlarged housing integral with the slide, a cylindrical bore therein having an open end adjacent to the other end of the spindle, a motor stator mounted within said bore, a motor armature within the stator which is fixedly mounted on the spindle to rotate the same, adjustable radial and end thrust bearings for the other end of said spindle on the opposite end of said armature from the first bearing, and a removable end cap supporting said latter bearings and closing the open end of said cylindrical bore to permit access to the motor parts.

2. A grinding machine comprising a base, a wheel slide, a rotatable wheel spindle mounted on said slide, a grinding wheel on said spindle, an adjustable bearing on the slide to support the end of the spindle adjacent to the grinding wheel, an enlarged portion integral with said slide, a cylindrical bore therein having an open end adjacent to the other end of the spindle, a motor stator removably mounted within said bore, an armature within said stator and fixedly mounted on the spindle to rotate the same, a readily removable end cap for closing the open end of said bore, an adjustable bearing supported by said cap for rotatably supporting the other end of the wheel spindle on the opposite side of the armature from the first bearing, and an air circulating fan mounted outside of said second bearing to circulate air around and between the motor parts to cool the same during grinding.
